UNITED STATES PATENT OFFICE.

WILLIAM H. MANAHAN, OF ARROWSMITH, ILLINOIS.

OIL-BARREL SUPPORT.

1,326,077.

Specification of Letters Patent. Patented Dec. 23, 1919.

Application filed September 27, 1919. Serial No. 326,786.

To all whom it may concern:

Be it known that I, WILLIAM H. MANAHAN, a citizen of the United States, residing at Arrowsmith, in the county of McLean 5 and State of Illinois, have invented a new and useful Oil-Barrel Support, of which the following is a specification.

The present invention relates to barrel or other receptacle supporting stands, the 10 principal object being to provide a support which will retain the receptacle in tilted position so that the contents of the same may be dispensed therefrom.

A further object of the invention is to 15 provide a stand for holding a receptacle in various angular positions while the contents thereof is being poured therefrom and which may be locked in such position.

Still another object of the invention is 20 to provide a receptacle supporting frame which includes a supporting frame adapted to receive the barrel or other receptacle which is equipped with means for locking the barrel in the frame, the locking means 25 being such as to be readily released to withdraw the barrel from the stand and permit a new one to be placed therein.

Another general object of the invention is 30 to provide a barrel stand which is of rigid and simple construction, and which may be manufactured and sold at a minimum cost.

With the above and other general objects and advantages in mind, the invention consists of the combinations of elements, constructions and arrangements, operations and formations, and general assemblage the details of which will be hereinafter enlarged upon and recited in the subjoined claims.

40 Referring to the drawing:

Figure 1 illustrates a transverse sectional view through a support constructed in accordance with the present invention, a barrel being disclosed in dotted lines.

45 Fig. 2 illustrates a front elevational view of the support.

Fig. 3 illustrates a side elevational view of the same, disclosing the barrel and frame in its tilted position, in dotted lines.

50 Referring to the drawing wherein like characters of reference designate like parts, there is provided a substantially U-shaped bracket 5 which is adapted to rest upon the ground. Supporting bars or horizontal 55 ground engaging legs are secured to the U-shaped bracket, the inner faces of the bars

being provided with recesses 7 in which the U-shaped bracket is snugly received.

Attached to the bars 6 at their upper ends is a U-shaped member 8, this latter U-shaped member 8 being superposed upon the brackets 5 and the parallel vertical legs of both being attached together through the medium of fastenings 9. Fixed upon the face of each of the vertical legs of the U- 65 shaped member 8 are plates 10 having rack teeth formed upon one side thereof.

There is provided a substantially rectangular frame 12 from the opposite sides of which extend trunnions 13 that are journaled through the plates 10 and upstanding ends of the U-shaped member 8. The outer faces of these bars are recessed as at 14 so that the recesses 14 receive the plates. Lugs 15 are mounted in these recesses and are 75 engageable with the rack teeth to retain the frame in various angular positions.

Intersecting the rectangular frame 12 is a U-shaped member 16 which co-operates with the frame in supporting the barrel. 80 The lower end of this U-shaped member 16 terminates in a beveled keeper 17. A recess 18 is provided rearwardly of this keeper and is adapted to receive a substantially rectangular enlargement 18 formed upon the 85 right-angularly extending extremity or latch bar 19, hinged as at 20 to the opposite end of the U-shaped member 16.

In the use of the device the barrel is supported in the frame and locked therein 90 through the medium of the latch bar. When it is desired to pour part of the contents of the can therefrom, the frame is tilted to the required angle and the pivoted pawl engaged with any of the rack teeth to prevent 95 the frame swinging beyond the desired angle, the frame being swung back to the vertical position after the pouring operation.

The embodiment of the invention here 100 shown and described is considered the preferred construction but it will be understood that the same may be modified and altered in many respects and that such limits of modification are only governed by what 105 is claimed.

What is claimed is:

1. In a barrel support upstanding parallel supporting members, a pivoted frame journaled in the upstanding supporting 110 member, a U-shaped member disposed centrally of the frame and secured thereto, the

frame and **U**-shaped member supporting a receptacle therein, and a latch bar having one end pivoted to the **U**-shaped member and its opposite end adapted to be engaged with the opposite end of the **U**-shaped member.

5 2. In a device of the character described, a substantially rectangular frame supported for pivotal movement, a **U**-shaped member extending at right-angles to the frame and secured thereto, the **U**-shaped member being provided with a substantially rectangular recess in one face thereof, said end terminating in a beveled keeper, and a latch bar pivoted to one end of the **U**-shaped member, and a rectangular enlargement upon the opposite end of the latch bar engageable in the recess.

10 3. In a barrel supporting stand, a substantially **U**-shaped bracket adapted to rest upon the ground, feet extending at right-

angles to the **U**-shaped bracket and secured thereto, a second **U**-shaped member positioned upon the feet and connected with the upstanding legs of the bracket, plates secured to the vertical legs of the second named **U**-shaped member provided with teeth, and a swinging sketch frame for retaining a receptacle therein journaled in the vertical legs of the second **U**-shaped member, and pivoted pawls carried thereby engageable with the teeth to prevent the frame being swung beyond a predetermined point.

15 25 In testimony that I claim the foregoing as my own, I have hereto affixed my signature in the presence of two witnesses.

WILLIAM H. MANAHAN.
